UNITED STATES PATENT OFFICE.

WALTER HENRY ELGOOD, OF NEW CROSS, ENGLAND.

WIREWORK.

SPECIFICATION forming part of Letters Patent No. 789,596, dated May 9, 1905.

Application filed August 15, 1904. Serial No. 220,826.

To all whom it may concern.

Be it known that I, WALTER HENRY ELGOOD, a subject of the King of Great Britain and Ireland, residing at 2 Reaston street, New Cross, 5 in the county of London, England, have invented certain new and useful Improvements in Wirework; and I do hereby declare the following to be a full, clear, and exact description of the invention, such as will enable others skilled 10 in the art to which it appertains to make and use the same.

This invention relates to improvements in wirework, and has for its object to simplify its structure by dispensing with the small binding-wire now usually employed in laced wirework.

According to this invention I take tubes of any desired size, material, and section, according to the class and work required. The 20 said tubes I provide with transverse slots for the reception of the wires. The number of the said tubes and the distance between the slots will depend upon the mesh required. The wires are held in the said slots by means 25 of wires of any section running longitudinally through the said tubes on the sides where the slots are provided, such longitudinal wires being suitably fastened at each end.

Wirework may be made according to this 30 invention by unskilled persons, and it will be found to be much stronger than when the strands are laced with binding-wire, as heretofore.

In the accompanying drawings, Figure 1 35 shows elevation of a piece of straight parallel wirework constructed according to my invention. Fig. 2 shows a vertical and transverse section of same, taken through the line A B, Fig. 1. Fig. 3 shows cross-section of one of 40 the slotted tubes. Fig. 4 shows elevation of one of the slotted tubes shown in Fig. 6. Fig. 5 shows end view of same. Fig. 6 shows a plan of a piece of circular wirework constructed on the same principle as that depicted in 45 Fig. 1. Fig. 7 illustrates the method of making diamond-shaped wirework. Fig. 8 shows plan of same.

The same letters of reference denote the same parts in all the views.

50 *a* shows the wire, which may be bent back-

ward and forward, as shown at Fig. 1, or I may have the wire in lengths.

b shows slotted tubes, preferably made of metal.

To construct wirework according to this invention, the wires *a* are placed in the slots *c* of the tubes *b*. The said wires *a* are held firmly in position by other wires, *d*, being inserted in the tubes *b*, and these wires *d* may be fastened off at their ends by turning them round 60 the top and bottom wires *a*, as shown at Figs. 1 and 2.

At Fig. 6 I have shown a way of making a circular piece of wirework. In this case I have slightly flattened the tubes *b* on their upper surfaces.

At Fig. 7 I have shown a way of making diamond-shaped wirework. In this case the tubes *b* are formed of a flat strip bent round, so as to form a worm or spiral, thus forming 70 diagonal spaces or slots *e*, in which the wires *a* take and are held firmly in position by the vertical wire *d*, as before described.

I may have any desired number of tubes *b* (of any suitable cross-section) to a given length 75 of wirework, according to the strength required. I may form the tubes from a sheet of metal (not jointed) and suitably punched or perforated in the flat to produce the aforesaid slots.

80 All kinds of wirework articles may be made according to this invention without any skilled labor being necessary, and the wirework so constructed will be much stronger than wirework as hitherto made.

85 What I claim, and desire to secure by Letters Patent of the United States of America, is—

1. Wirework consisting of slotted tubular members, wire strands resting in said slots, 90 and means within said members extending longitudinally thereof adjacent said slots for retaining said strands in such position, substantially as described.

2. Wirework consisting of slotted tubular 95 members, wire strands resting in said slots and retaining-wires extending longitudinally through said members and engaging said strands, substantially as described.

3. Wirework consisting of a plurality of 100

slotted tubes, wire strands resting in the base of said slots and a straight retaining - wire passed longitudinally through each of said tubes over said strands and under said slots, 5 substantially as described.

4. Wirework consisting of tubular members formed of spirally-wound sheets leaving slots between the convolutions, wire strands resting in said slots, and retaining-wires extending longitudinally through said members and engaging said strands, substantially as described. 10

5. Wirework consisting of tubular members formed of spirally-wound sheets leaving slots 15 between the convolutions, oppositely-disposed wire strands resting in the base of said slots,

and straight retaining-wires passed longitudinally through said members and between said oppositely-disposed strands, substantially as described. 20

6. Wirework consisting of tubular members having reversely-arranged diagonal slots oppositely disposed in their surfaces, wire strands resting in said slots, and retaining-wires extending within said members and between said 25 strands, substantially as described.

In testimony whereof I affix my signature in presence of two witnesses.

WALTER HENRY ELGOOD.
